UNITED STATES PATENT OFFICE.

PAUL LUCAS, OF BERLIN-FRIEDENAU, GERMANY.

WICKLESS BURNER FOR USE IN CONNECTION WITH PETROLEUM OR OTHER LIQUID HYDROCARBONS.

Application filed March 25, 1922. Serial No. 546,857.

To all whom it may concern:

Be it known that I, PAUL LUCAS, a citizen of the German Republic, and resident of Berlin-Friedenau, Germany, have invented 5 a certain new and useful Improved Wickless Burner for Use in Connection with Petroleum or Other Liquid Hydrocarbons.

This invention relates to a wickless burner in which petroleum or other liquid hydro- 10 carbons may be burned.

According to this invention the burner-tube extending upwards from the fuel-receptacle consists of German silver or another alloy which is a comparatively bad conductor 15 of heat, so that the tightening between the burner tube and the fuel receptacle may be effected by the medium of a screw-threaded connecting member, simply by a disk of cork or an equivalent organic substance 20 without any fear of this packing disk being ignited during the service.

Owing to the strong heating of the burner-tube and the fuel-receptacle, the tightening of the joint between these parts could hitherto 25 be effected only by an asbestos packing member or a metallic packing member, but both materials have proved unsatisfactory in practical service.

The invention offers also the further considerable advantage that the burner-tube 30 may be grasped during the service (or immediately thereafter) at its lower end and, if desired, may be turned, without any danger of burning one's hand, the fact being 35 that the tightening place remains always cool.

Igniting a burner of the before-mentioned improved kind is effected by means of an ignition tube arranged outside of the pre-heating or starting bowl and containing a wick which sucks the liquid fuel from that bowl. Owing to the ignition tube being located outside of the preheating or starting bowl, the material advantage is obtained 45 that the fuel getting into the ignition tube gasifies not too quickly, and by a certain quantity of the fuel being sucked up by the wick portion within the ignition tube a certain store of fuel is accumulated which lasts 50 for a comparatively long time and ensures the ignitability also in this direction.

As, by the employment of the German silver tube, an easily disconnectable connection between the burner and the receptacle 55 is brought about, it is easily possible to ex-

change a cooking or heating burner for an incandescence-light burner, and reversely, both burners having the same thread. In such a construction the provision is necessary that the grate, or the supporting ring 60 respectively, be removable without any difficulty, and may also easily be reinserted. The grate or ring is, for this purpose, provided with hinged feet which are removable together with the said grate or ring. 65 The lower ends of said feet are, preferably, hook-shaped, these hooks having horizontal recesses receiving portions of an annular projection formed at the fuel receptacle by a circumferential groove. 70

Thus, the grate or supporting ring having been put in place upon the receptacle, a downwardly directed pressure acting upon the junction places is produced whereby the stability of the upper supporting structure 75 is warranted and the feet are securely prevented from spreading.

I am aware of a known structure for a similar purpose, having feet hinged to a supporting ring and carrying the fuel receptacle 80 so-to-say floatingly; there are in these feet rounded recesses, the shape of which is such that they cannot prevent the feet from spreading under the pressure produced by the supporting ring and its load. 85

If a cooking device constructed according to the present invention is to be changed into an illuminating burner, the feet supporting the ring are drawn off the fuel receptacle, the ring is removed, and the heating or cooking burner is replaced by an illuminating burner which is attached to the fuel receptacle in lieu of said other burner.

In order to make my invention more clear, I refer to the accompanying drawings in 95 which similar letters of reference denote similar parts throughout the several views, and in which Figure 1 is a vertical section through a petroleum-burner constructed according to this invention, the fuel receptacle being shown partly in side-view. Fig. 2 is a vertical section solely through the burner proper having, in this instance, a special ignition tube. Fig. 3 is a side-view of the complete burner, as shown in Fig. 1 100 but turned into a cooking or heating burner by the addition of an appropriate upper structure, as shown. Fig. 4 is a side-view of some members of said structure, viz. one of its feet, in combination with a portion of 105 110

the supporting ring, to which all feet are hinged. Fig. 5 is a plan of the supporting ring. And Fig. 6 shows the fuel receptacle provided with an illuminating burner instead of with a cooking or heating burner, and furnished with the other appliances a lamp requires.

The fuel receptacle 1 is provided in known manner with an air pump 2 and a filling branch 3 having a ventilating screw 3^a. The burner tube 6 which is provided at its upper end with the nozzle 7 consists of German silver or another alloy which is a comparatively bad conductor of heat so that the lower portion of the burner tube which is to be packed remains cool during the service. The burner tube is held in place by a flanged sleeve 4 forming a kind of cap-nut and effecting the tightening of the junction with aid of a packing ring 5 placed between the flange of 4 and the opposite annular portion of the top of the receptacle 1. The ring 5 consists, preferably, of cork or an equivalent substance.

25 The burner proper consists of a plurality of parts which are not parts of this invention. There is a burner head 9 with air-supply apertures 8, a basin-shaped annular disk 10 which is soldered to the head 9, and a pre-heating or starting basin 12.

In the form of construction shown in Fig. 2, the basin 12, which is attached to the lower end of a piece of tube 13 extending down from the burner head, is provided with an upwardly extending ignition-tube 14 containing a wick 15. The ignition tube is, in the example shown somewhat oblique, but it may be perfectly vertical as well; it communicates with the basin 12 through an aperture 16 and ignites in known manner the gases generated within the burner and escaping through the lateral apertures of its head.

45 Referring to Figures 3, 4 and 5 in which the fuel receptacle and the burner are furnished with the means for supporting a cooking vessel, these means consist of a plurality of feet 20 which are U-shaped in transverse section, as shown at 21 in Figs. 3 and 4, and are hinged at their upper ends to a ring 19 having downwardly extending lugs to which the feet 20 are hinged by means of pins 22. The lower ends of the feet 20 form hooks 23 which engage a circumferential groove 18 provided in the receptacle 1. The hooks 23 fit tightly into the groove 18.

If the upper structure (19, 20 etc.) shall be removed from the receptacle and the burner, the hooks 23 are drawn out of the groove 18 and the upper structure is collapsed by turning the feet inwards as shown in dotted lines in Fig. 4.

60 Referring now to Fig. 6 the cooking burner is here replaced by an illuminating burner

also attached to a tube 6 having a nozzle, as shown. This burner has at its lower end a space 24 provided for the preheating or starting purpose. 25 are lateral apertures affording access to the space 24. The upper burner-tube proper consists, preferably, of copper and encloses a smaller tubular member 27^b which communicates at its lower end with the nozzle of the tube 6, as well as with lateral apertures 26 through which air is conducted to the petroleum vapor rising in the tubular member 27.

27^a is a short U-shaped connecting member between the inner space of the insertion 27 and the space between this insertion and the burner tube. A small portion of the mixture rising in the insertion 27 escapes through the communication afforded by the piece 27^a into that annular intermediate space and gets then downwards to apertures 27 provided in the copper burner tube. These small mixture currents are ignited and form auxiliary flames. The main portion, however, of the mixture escapes at the top of the burner tube where there are 80 apertures 28 for that purpose. This portion of the mixture produces the heating flame for the incandescence body which is shown in dotted lines.

The lamp shade 29 is supported by a ring 95 provided with standards 30. The configuration of these latter at their lower ends is practically the same as with the feet 20 of Fig. 3.

The tube 6 is provided at its lower end 100 with a rather broad flange 31 forming a kind of foot for the burner when out of use. The parts below that flange or foot are the same as in Fig. 1.

Having now described my invention, what 105 I claim as new and desire to secure by Letters Patent of the United States is:

1. A wickless cooking and illuminating device for use in connection with petrol and the like, comprising in combination, a receptacle adapted to receive the liquid fuel; two exchangeable burner-supporting tubes, either of which is adapted to be attached to said receptacle; a cooking burner affixed to one of said tubes; an illuminating burner 110 affixed to the other of said tubes; and means for forcing the liquid fuel up into the just employed burner supporting and fuel supplying tube.

2. A wickless cooking and illuminating 120 device for use in connection with petrol and the like, comprising in combination, a receptacle adapted to receive the liquid fuel; two exchangeable burner-supporting tubes consisting of a metal that is a bad conductor 125 of heat and being each adapted to be attached to said receptacle; a flange secured to each tube at its fastening end; a packing ring adapted to be arranged between said flange and the opposite portion of the top 130

of the receptacle and consisting of an organic substance; a cooking burner affixed to one of said tubes; an illuminating burner affixed to the other of said tubes; and means 5 for forcing the liquid fuel up into the just employed burner-supporting and fuel supplying tube.

3. A wickless cooking and illuminating device for use in connection with petrol 10 and the like, comprising in combination, a receptacle adapted to receive the liquid fuel; two exchangeable burner-supporting tubes, either of which is adapted to be attached to said receptacle; a cooking burner affixed to 15 one of said tubes; an ignition basin attached to the same tube below said burner; an ignition tube extending upwards from said basin laterally from said tube; an illuminating burner affixed to the other of said tubes; 20 and means for forcing the liquid fuel up into the just employed burner-supporting and fuel supplying tube.

4. A wickless cooking and illuminating device for use in connection with petrol and 25 the like, comprising in combination, a receptacle adapted to receive the liquid fuel; two exchangeable burner-supporting tubes, either of which is adapted to be attached to said receptacle; a cooking burner affixed to 30 one of said tubes; an illuminating burner affixed to the other of said tubes; a foot attached to the lower end of this other tube; and means for forcing the liquid fuel up into the just employed burner-supporting and 35 fuel-supplying tube.

5. A wickless cooking and illuminating device for use in connection with petrol and the like, comprising in combination, a receptacle adapted to receive the liquid fuel; 40 two exchangeable burner-supporting tubes, either of which is adapted to be attached to said receptacle; a cooking burner affixed to one of said tubes; an illuminating burner affixed to the other of said tubes; a detachable tripod adapted to be attached to the 45 upper rim of the said receptacle; and means for forcing the liquid fuel up into the just employed burner-supporting and fuel supplying tube.

50 6. A wickless cooking and illuminating device for use in connection with petrol and the like, comprising in combination, a receptacle adapted to receive the liquid and having a circumferential groove near to its

upper rim; two exchangeable burner supporting tubes, either of which is adapted to be attached to said receptacle; a cooking burner affixed to one of said tubes; an illuminating burner affixed to the other of said tubes; a detachable tripod adapted to be 55 attached to the upper rim of the said receptacle and having at the lower ends of its feet projections adapted to engage said receptacle groove; and means for forcing the liquid fuel up into the just employed burner-supporting and fuel supplying tube.

7. A wickless cooking and illuminating device for use in connection with petrol and the like, comprising in combination, a receptacle adapted to receive the liquid fuel; 70 two exchangeable burner-supporting tubes, either of which is adapted to be attached to said receptacle; a cooking burner affixed to one of said tubes; an illuminating burner affixed to the other of said tubes; two exchangeable tripods, either of which is adapted to be attached to the upper rim of the said receptacle and of which one is adapted for use in connection with the cooking burner and the other is adapted for use in 80 connection with the illuminating burner; and means for forcing the liquid fuel up into the just employed burner-supporting and fuel supplying tube.

8. A wickless cooking and illuminating 85 device for use in connection with petrol and the like, comprising in combination, a receptacle adapted to receive the liquid and having a circumferential groove near to its 90 upper rim; two exchangeable burner supporting tubes, either of which is adapted to be attached to said receptacle; a cooking burner affixed to one of said tubes; an illuminating burner affixed to the other of said tubes; two exchangeable tripods, either of which is 95 adapted to be attached to the upper rim of the said receptacle and has at the lower ends of its feet projections adapted to engage said receptacle groove; and means for forcing liquid fuel up into the just employed burner-supporting and fuel supplying tube.

In testimony whereof I affix my signature in presence of two witnesses.

PAUL LUCAS.
